UNITED STATES PATENT OFFICE.

CHARLES G. NEUBARTH, OF NEW YORK, N. Y.

DESIGN FOR LACE TRIMMING.

No. 37,522.

Specification for Design.

Patented Aug. 29, 1905.

Application filed June 9, 1905. Serial No. 264,525. Term of patent 3½ years.

To all whom it may concern:

Be it known that I, CHARLES G. NEUBARTH, a citizen of the United States, and a resident of the city of New York, borough of the Bronx, in the county and State of New York, have invented a new, original, and ornamental Design for a Lace Trimming, reference being had to the accompanying drawing, in which the figure shows the lace in plan.

I claim—

The ornamental design for a lace trimming herein shown.

CHARLES G. NEUBARTH.
